UNITED STATES PATENT OFFICE.

RUSSELL C. FIELDS AND ELMER F. FIELDS, OF PIPESTONE, MINNESOTA.

ROTATABLE SEESAW.

Application filed July 8, 1922. Serial No. 573,553.

To all whom it may concern:

Be it known that we, RUSSELL C. FIELDS and ELMER F. FIELDS, citizens of the United States, residing at Pipestone, in the county of Pipestone and State of Minnesota, have invented certain new and useful Improvements in Rotatable Seesaws, of which the following is a specification.

Our invention relates to rotatable seesaws, and an object is to provide a device of this character having a see-saw board which can be caused to rotate as well as swing up and down and which can be used with safety by children without liability of getting their fingers pinched. Another object is to provide a device of this character which can be readily assembled and taken apart so as to be convenient for transportation.

The full objects and advantages of our invention will appear in connection with the detailed description, and the novel features embodied in our inventive idea will be particularly pointed out in the claims.

In the accompanying drawings, Fig. 1 is a top plan view of our device. Fig. 2 is a side elevational view thereof. Fig. 3 is a view in vertical section on the line 3—3 of Fig. 5. Fig. 4 is a view in vertical section on the line 4—4 of Fig. 3. Fig. 5 is a view in vertical section on the line 5—5 of Fig. 1.

As shown in the drawings, the casting 10 is supported by legs 12 and the upper surface of this casting is provided with a cylindrical projection 14 which is received in a corresponding recess in the lower surface of a second or upper casting 16. A bolt 18 holds the two castings together so that the upper casting 16 may be rotated upon the lower casting 10. Secured by screws 20 to the upper side of the casting 16 is a horizontal cylindrical member 22 which oscillatingly receives a rod 24 which is held in place by a pin 26 secured to the rod and working in an arcuate slot 28 in the upper half of the cylindrical member. A see-saw board of the desired length is secured to the rod 24 by screws 32. As

shown in Fig. 5, the lower surface of the board 30 is cut out to receive the upper portion of the cylindrical bearing member 22. As will appear from Figs. 4 and 5, the upper portion of the member 22 is reduced in length whereby it is not necessary to cut as long a groove in the board as would otherwise be the case.

The operation and advantages of our invention will now be obvious. The board 30 will ordinarily be of such length that its ends will hit the ground before the board touches the casting 16. The entire device is, therefore, so constructed that a child cannot get his fingers pinched while by pushing with his feet on the ground he can cause the board to rotate as well as swing up and down.

We claim:

1. A rotatable see-saw comprising a support, a casting mounted on said support, a second casting mounted for rotation in a horizontal plane upon said first casting, said castings having a cooperating projection and recess to constitute a bearing for such movement, a horizontal cylindrical member secured to the upper side of said second casting, a rod mounted for oscillating in said cylindrical member, and a see-saw board secured to said rod.

2. A rotatable see-saw comprising a support, a casting mounted on said support, a second casting mounted for rotation in a horizontal plane upon said first casting, said first casting having a cylindrical projection in its upper surface fitting a recess in the lower side of said second casting, a horizontal cylindrical member secured to the upper side of said second casting, a rod mounted for oscillation in said cylindrical member, a pin secured to said rod and working in a slot in said cylindrical member, and a see-saw board secured to said rod.

In testimony whereof we hereunto affix our signatures.

RUSSELL C. FIELDS.
ELMER F. FIELDS.
